CLAIM

The ornamental design for a housing for a circular saw, as shown and described.

DESCRIPTION

FIG. 1 is a right side perspective view from the front of a housing of a circular saw showing my new design;
FIG. 2 is a right side elevational view of the housing;
FIG. 3 is a left side elevational view of the housing;
FIG. 4 is a front elevational view of the housing;
FIG. 5 is a rear elevational view of the housing;
FIG. 6 is a top plan view of the housing;
FIG. 7 is a bottom plan view of the housing.
FIG. 8 is a right side elevational view of the housing of FIG. 2 shown separately; and,
FIG. 9 is a left side elevational view of the housing of FIG. 3 shown separately.
